UNITED STATES PATENT OFFICE.

JOHN LATHROP GRAY, OF ST. LOUIS, MISSOURI.

OIL-CRACKING STILL.

1,331,909.

Specification of Letters Patent. Patented Feb. 24, 1920.

Application filed February 21, 1917, Serial No. 150,026. Renewed November 13, 1919. Serial No. 337,885.

To all whom it may concern:

Be it known that I, JOHN LATHROP GRAY, a citizen of the United States, residing at St. Louis, Missouri, have invented certain new and useful Improvements in Oil-Cracking Stills, of which the following is a clear, full, and exact description.

This invention relates to an improved apparatus for superheating liquids or vapors while the same are under great pressures. The improvement is capable of wide use, but the present embodiment thereof is more particularly adapted for use in connection with many of the present-day processes for distilling and cracking petroleum, in order to obtain larger fractions of the low boiling hydrocarbons and may therefore be termed an oil cracking still.

In many of these cracking processes it is usual to heat the oil to comparative high temperatures, running from 450° to 900° F. and at the same time confine it so that comparatively great pressures are produced, *i. e.*, upward of 70 lbs. per square inch, in order to facilitate the splitting up of the various hydrocarbons of the oil. The oil is usually heated in pipes of comparatively small cross-section, the coils of which are located in a furnace or other heating means. The oil conducting pipes should be of steel or wrought iron in order to withstand the pressure to which they are subjected, but it has been found that such steel or wrought iron pipes, even though filled with oil, rapidly deteriorate and burn out when exposed directly to a high degree of heat.

One of the many objects therefore of the present invention is to devise a construction which will overcome this difficulty, and which while protecting the pipes from burning out, yet does not prevent the communication of the desired heat to the oil or vapor within the pipes. This is accomplished by embedding the steel or wrought iron oil-carrying pipes within a casing of cast iron and in intimate contact therewith so that the cast iron receives the direct application of heat, and conducts it to the pipes embedded therein in such a uniform and diffusive manner as to greatly increase the durability and longevity of the pipes. A further object of the invention is to provide an apparatus of this kind which may be easily taken apart, cleaned and repaired, and in general improve the efficiency of such oil cracking stills.

In the preferred embodiment of my invention shown in the accompanying drawings,

Figure 1 is a side elevation of the still 60 installed in a suitable furnace, the latter being shown in section;

Fig. 2 is a horizontal section of said still;

Fig. 3 is a partial section along line 2—2 of Fig. 1; and

Fig. 4 is a detached detail of one of the return bends for connecting adjacent ends of pipe.

Referring more particularly to the drawings, 1 indicates a casing of cast iron, preferably in the form of a hollow cylinder, with lugs 5 and 6 for supporting the same upon the walls 7 and 8 of a suitable furnace 17. The furnace may be of any suitable construction but preferably arranged to support 75 the still horizontally and to direct the furnace gases around all sides of the still. As shown, the fire box 14 is below the still and cross partitions 15 and 16 between the side walls 7, 8 cause the heated furnace gases to 80 pass first along the underside of the still, then through the hollow interior and finally back over the top of the still to reach the stack 18 of the furnace.

The cylindrical casing 1 has a thick cylindrical wall, within which is embedded, in intimate contact therewith, a plurality of straight lengths of steel or wrought iron pipes such as 2. As shown in Fig. 2, these straight lengths of pipe extend through the 90 cylindrical wall of the casing from end to end parallel to the axis of said casing, and have exposed portions 3 and 4 protruding from each end of the casing.

The ends of each pipe are provided with 95 suitable flanges such as 9. Return bends 10, preferably formed with one long leg 11 and one short leg 12, together with flanges 13 upon the end of each leg, may be suitably employed for connecting the ends of two adjacent pipes, such for instance as the right-hand end of pipes 2' and 2² (Fig. 2). The left-hand end of pipe 2² is then connected by a similar bend to the left-hand end of pipe 2³. In a similar manner, the alternate 100 ends of adjacent pipes are connected together by return bends so as to form a continuous conduit running back and forth through the cylindrical wall of the casing and extending from the entering pipe 2' at 110 the bottom, around one side of the casing, up to the exit pipe 2⁴ at the top of the cas-

ing. A similar but separate continuous conduit is formed by the pipe lengths on the right-hand side of the casing (looking at Fig. 3) with pipe 2⁵ as an entering pipe and 5 pipe 2⁶ as the exit pipe. An inlet valve 19 is provided for pipe 2' and a similar inlet valve 20 for pipe 2⁵. Outlet valves 21 and 22 are also provided for the outlet pipes 2⁴ and 2⁶ respectively, and it is through the 10 operation of these outlet valves that the pressure within the pipes may be controlled. In Fig. 1 the return bend connections are shown at the left only for half of the pipes, namely, the series 2' to 2⁴, and at the right 15 of said view the return bends for only the lower half of the other series 2⁵ to 2⁶ are shown for the sake of clearness in illustration.

It will be noted that the return bends 10 20 are detachable from the ends of the straight pipe lengths so that the apparatus may be opened up at any time and the pipes cleaned out, or new straight lengths inserted when desired, as I find this a great improvement 25 over a continuous coil arrangement. The exposed protruding ends of the pipes with the return bends also take care of the expansion and contraction of the pipes, due to changes of temperature, and provide for 30 an elastic system of heating coils. Furthermore, in order to locate the pipe lengths close together within the casing, the flanges 9 upon the end of the pipe lengths are staggered, whereby the flanges of two adjacent 35 pipes do not come together to widen the space which would otherwise be required between said pipes. This staggered overlapping arrangement is preferably accomplished by having each pipe length extending 40 farther from one end of the casing than its adjacent neighbor, and extending less far from the other end of the casing than its neighbor. In this way a uniform straight length of pipe may be used for the apparatus. It will also be noted that the thickness 45 of cast iron casing at no point surrounding the steel or wrought iron pipe is substantially less than the radius of said pipe. No exact measurements need be given 50 for this thickness of casing around the pipes, as of course it may be varied to said requirements, depending upon the heat to be applied to the pipes and the interior pressure to be withstood by the pipes.

55 I am well aware that various changes in details and modifications of structure may be made over the preferred form of my

apparatus herein described and shown, and therefore I do not wish my invention to be limited to this precise embodiment thereof. 60 Moreover, although the subjoined claims specify wrought iron pipe, it is understood that suitable steel pipe may be used in place thereof, without departing from my invention. 65

What I claim as new is:—

1. A superheater comprising a plurality of straight lengths of wrought iron pipes arranged in a cylindrical series, each length of pipe having a covering of cast iron in 70 intimate contact therewith.

2. A superheater, comprising a hollow cylindrical casing of cast iron, and having straight lengths of wrought iron pipe embedded in the cylindrical wall thereof and 75 extending therethrough parallel to the axis of said cylinder.

3. A superheater, comprising a hollow cylindrical casing of cast iron, and having straight lengths of wrought iron pipe embedded in the cylindrical wall thereof and extending therethrough parallel to the axis of said cylinder, and return bends connecting 80 together adjacent ends of pipe to form a continuous conduit back and forth through 85 said casing.

4. A superheater, comprising a hollow cylindrical casing of cast iron, horizontally supported and having straight lengths of wrought iron pipe embedded in the cylindrical wall thereof and extending therethrough parallel to the axis of said cylinder, return bends connecting together adjacent 90 ends of said pipe to form one continuous conduit leading from the lower part of said casing back and forth through the cylindrical wall thereof at one side of said casing, to the upper part of said casing, and a separate continuous conduit from the lower part of 95 said casing back and forth through the cylindrical wall thereof at the other side of said casing to the upper part of said casing. 100

5. The combination with a superheater, comprising a hollow cylindrical casing having pipes embedded in its cylindrical wall, 105 of a furnace for supporting said casing horizontally, and partitions in said furnace for directing said heated gases successively along the lower side, inside and upper side of said cylindrical casing. 110

Signed at New York, N. Y., this 6th day of February, 1917.

JOHN LATHROP GRAY.
